(57) CLAIM

The ornamental design for the bottle, as shown and described.

DESCRIPTION

FIG. 1 is a front perspective view of a bottle, showing my new design;

FIG. 2 is a front view thereof, the back view being a mirror image;

FIG. 3 is a right side view thereof, the left side being a mirror image;

FIG. 4 is a top view thereof; and,

FIG. 5 is a bottom view thereof.

The broken lines shown in the figures are for illustrative purposes only and form no part of the claimed design.
